UNITED STATES PATENT OFFICE.

FREDERICK WEHINGER, OF WATERBURY, CONNECTICUT, ASSIGNOR TO WATERBURY CLOCK CO., OF WATERBURY, CONNECTICUT, A CORPORATION.

RACK-AND-SNAIL STRIKING CLOCK.

Application filed June 6, 1923. Serial No. 643,611.

To all whom it may concern:

Be it known that I, FREDERICK WEHINGER, a citizen of the United States, residing at Waterbury, in the county of New Haven and State of Connecticut, have invented a new and useful Improvement in Rack-and-Snail Striking Clocks; and I do hereby declare the following, when taken in connection with the accompanying drawings and 10 the characters of reference marked thereon, to be a full, clear, and exact description of the same, and which said drawings constitute part of this application, and represent, in—

15 Fig. 1 an edge view of a striking clock of the rack-and-snail type embodying my invention, the parts being shown in their normal positions.

Fig. 2 a front view thereof.

20 Fig. 3 a view corresponding to Fig. 2 but showing the parts in their warned positions.

Fig. 4 a detached perspective view of my improved lock-work lifting-unit.

25 Fig. 5 a corresponding view of my improved lock-work locking-unit.

My invention relates to an improved striking clock of the rack-and-snail type, the object being to simplify and reduce the cost of assembling and adjusting such clocks and to 30 increase the reliability of their performance.

With these ends in view, my invention consists in a striking clock of the rack-and-snail type having certain details of construction and combinations of parts as will be 35 hereinafter described and particularly pointed out in the claim.

In carrying out my invention, as herein shown, I discard the sheet-metal lifting-lever and the sheet-metal locking-lever heretofore employed in rack-and-snail striking clocks, and replace them by means of a lock-work lifting-unit and a lock-work locking-unit, both pivotally mounted in and between the respective front and rear movement- 40 plates 10 and 11 of the clock, and, therefore, advantageously positioned for co-action for the discharge of their respective functions.

45 My improved lock-work lifting-unit (Fig. 4) consists of a staff 12 provided at its ends with journals 13, by which it is pivotally mounted for rocking movement in the said movement-plates 10 and 11 and carries a depending lifting-wire 14, the lower end of which is bent and flattened to form a lifting- 50 finger 15, which rides upon a double-pointed

lifting-cam 16 mounted upon the inner end of the center-arbor 17 of the clock-movement. The staff 12 also rigidly mounts a warning-wire 18 formed at its outer end with a warning hook 19 co-acting with a warning- 60 pin 20 in the fourth wheel 21 of the strike-train, which may be of any suitable construction and arrangement, the said pin 20 also discharging the function of a locking-pin, as will be presently described. 65

My improved lock-work locking-unit (Fig. 5) consists of a staff 22 having at its respective ends trunnions 23, by which it is journaled for limited rocking movement in and between the movement-plates 10 and 11 70 aforesaid. The said staff 22 has rigidly mounted in it a rack-wire 24 having its outer end bent forward at a right angle and flattened to form a rack-finger 25 which co-acts with the teeth of the rack 26 of an ordinary rack-and-snail mechanism. The staff 22 also mounts a wire-actuating hook 27, which rides upon the upper face of the warning-wire 18 of the lock-work lifting-unit, already described, so that, when the 80 staff 12 is rocked through the agency of the lifting-cam 16 and the lifting-wire 14, the lock-work locking-unit is operated for unlocking the strike-train. The said staff 22 also mounts a wire locking-hook 28, the bent 85 end of which co-acts with the combined warning and locking-pin 20 in the fourth wheel 21 to normally restrain the strike-train. The staff 22 is further provided with an upwardly-projecting stop-wire 29, which, 90 by engaging with the adjacent pillar 30 of the clock-movement, as shown in Fig. 2, serves to limit the rocking movement of the lock-work locking-unit and also provides for the attachment of one end of a spring 31 95 encircling the staff 22 and serving to hold it in its normal position with the finger 25 of the wire 24 in engagement with the rack 26. A corresponding spring 32, encircling the staff 12 of the lock-work lifting-unit provides for holding the same in its normal 100 position, in which the finger 15 of its lifting-wire 14 is maintained in engagement with the double-pointed lifting-cam 16.

The lock-work lifting- and locking-units, 105 above described, take the place, under my invention, of the sheet-metal lifting- and locking-levers commonly employed in striking clocks of the rack-and-snail type, one or both of these levers being pivotally mounted, 110

in ordinary practice, upon the front face of the front movement-plate. My improved lock-work lifting-units, with their wire members, on the other hand, are interposed 5 between the two movement-plates and are, therefore, advantageously positioned for co-action with the time- and strike-trains of the movement and on account of their particular character, are very easily and accurately adjusted, whereas, it is difficult to make these 10 adjustments where sheet-metal levers are used. Under my improvement, the delicate adjustments called for are effected by simply bending wires, whereas, in rack-and-snail striking clocks of the prior art, these 15 adjustments could be made only by filing sheet-metal levers, which, when filed, were to that extent mutilated and rendered less available for future adjustment. In another 20 view, by my invention, I have, without loss of accuracy and efficiency, carried over the advantages of the rack-and-snail type of striking mechanism into the cruder forms 25 of construction commonly associated with the count-wheel type of striking-clock, with all of the advantages thereto pertaining of simplicity, cheapness, and ease of adjustment.

Without entering into detailed description 30 of the other features shown, it may be added that the rack 26 is located at the end of a rack-arm 33, rocking upon a stud 34 in the front movement-plate 10. A rack-hook 35, connected with the arm 33 but standing in

front of the same, is formed with a forward- 35 ly-turned finger 36, which rides upon the steps of the snail 37, which is carried by a hub 38 over the front face of the hour-wheel 39.

Inasmuch as the several members of my 40 improved lock-work lifting- and locking-units discharge their functions in the same manner and in the same sequence as the corresponding features of the sheet-metal lifting- and locking-levers of rack-and-snail 45 striking clocks of the prior art, it is thought that a detailed description of their operation is unnecessary, since it is apparent to anyone familiar with such clock mechanisms. 50

I claim:

In a striking clock of the rack-and-snail type, the combination with the movement-plates thereof, of a time-train, a strike-train one wheel of which carries a combined warning-and-locking pin, rack-and-snail 55 mechanism, and a lock-work lifting-unit and a lock-work locking-unit, each consisting of a staff mounting wire-members and each having a member co-acting with the said combined warning-and-locking pin for 60 warning and locking the strike-train.

In testimony whereof, I have signed this specification in the presence of two subscribing witnesses.

FREDERICK WEHINGER.

Witnesses:
